UNITED STATES PATENT OFFICE.

DELBERT A. BEREAN, OF BARKER, AND WILLIAM W. TREVOR, OF LOCKPORT, NEW YORK, ASSIGNORS TO TREVOR MANUFACTURING COMPANY, OF LOCKPORT, NEW YORK.

MACHINE FOR OPERATING ON BARRELS OR OTHER CONTAINERS.

Application filed March 26, 1924. Serial No. 702,142.

This invention relates to improvements in machines for operating on barrels or other containers, and more particularly to barrel 5 chamfering, leveling and crozing machines.

In the manufacture of barrels, it is usual to arrange the staves in barrel formation in a setting up form, where they are drawn together and held in place by temporary truss hoops placed over the opposite ends of the 10 staves. These truss hoops are relatively thick metal rings tapered in accordance with the desired bilge of the barrel. One of the truss hoops is placed over each end of the barrel near the ends of the staves, after 15 which the hoops are driven tightly on the barrel by suitable hoop driving devices to a position in which they hold the barrel staves securely in the intended form, and so that the ends of the staves project outwardly 20 beyond the hoops a sufficient distance for the subsequent chamfering, leveling and crozing operations to be performed on the barrel ends. The trussing operation and the operations of chamfering, leveling and crozing 25 the ends of the staves are sometimes all performed in a single machine, but in the present instance the truss hoops are driven on the barrel by a separate machine or apparatus, whereby the truss hoops are driven to 30 predetermined distances from each other regardless of slight variations in the lengths of the staves, that is, the hoops on successive barrels of the same intended size will be all spaced apart the same distance irrespec- 35 tive of variations in the lengths of the barrels. This feature is taken advantage of in the machine of the present invention with the result that the barrels being trimmed with reference to the hoops as a gage, barrels 40 of uniform length are produced by the use of the machine.

One object of the invention is to provide a barrel or the like trimming or chamfering, leveling and crozing machine having improved means for receiving and supporting the barrels, on which they are firmly held and by which they are presented one end at a time to the action of the cutting devices.

Other objects are to provide a novel centering and gage device adapted to be engaged by and to cooperate with the truss hoops on the barrel so as to cause the cutting devices to be operated to make the barrels of predetermined length regardless of slight

variations in the lengths of the barrel staves, 55 or barrels before being trimmed; also to arrange said centering device on one of said barrel supporting means so that it may be adjusted relatively thereto for the purpose of accurately alining it relatively to the axis 60 of the rotary cutter head, so that when an end of a barrel is received by the centering and gage device, the barrel will be accurately alined, regardless of inaccuracies in 65 positioning of the barrel support on which said centering and gage means are supported; also to provide a plurality of interchangeable centering and gage devices, each having a truss hoop engaging portion of 70 different diameter but all having the same 75 outside dimensions so that they may be interchangeable on the machine and will be adapted to engage the adjustable positioning means and be automatically centered thereby as a result of the initial adjustment 75 of said positioning means for one of said devices, without further manipulation of said means.

Another object of the invention is the provision of adjustable stop devices for limiting 80 the movements of the barrel supporting devices to operative position for the purpose of stopping the movements of the barrel towards the cutting devices after the 85 chamfering and leveling operations, to permit the proper operation of the crozing device, and to limit the return stroke of the barrel supporting devices when one end of the barrel has been acted upon and is ready 90 to be taken from the machine, and reversed, 90 so that the other end may be similarly acted upon, after which the parts are again returned to a position such that the barrel may be finally removed.

Still other objects are to provide an improved crozing device and means for supporting and independently actuating said device, and to provide novel gage and stop devices for limiting the depth of cut of said 100 crozing device; also to improve and simplify machines of the sort mentioned so that such machines may be inexpensively manufactured and may be available to users of limited means; and to provide a machine of 105 this sort which is relatively small, light in weight and compact, so that it may be transported from place to place, as desired.

Other objects are to improve machines of

this sort in the other respects hereinafter specified and claimed.

In the accompanying drawings:

Fig. 1 is a side elevation of a barrel chamfering, leveling and crozing machine embodying the invention and showing the positions of the parts when not operating upon a barrel.

Fig. 2 is a plan view thereof.

Fig. 3 is a transverse sectional elevation thereof on line 3—3, Fig. 1, showing the supporting device for one end of the barrel.

Fig. 4 is a similar view showing the support for the other end of the barrel and part of the barrel centering means associated therewith.

Fig. 5 is a fragmentary longitudinal section of the machine showing the parts in position for centering a barrel relatively to the axis of the cutter head.

Fig. 6 is a similar view showing the barrel advanced to engaging position with the cutting devices.

Fig. 7 is a face view of the operating side of the cutter head.

Figs. 8 and 9 are fragmentary sectional elevations showing two different operative positions of the crozing device.

Fig. 10 is a longitudinal section of the actuating means for the crozing device, the parts being out of cutting position.

Fig. 11 is a similar view, but with the parts in cutting position.

Fig. 12 is a fragmentary section on line 12—12, Fig. 8, showing the pivot and an adjustable stop for the crozing device.

Fig. 13 is a plan view, and Fig. 14 is a transverse section of the chamfering knife of the cutter head.

Figs. 15 and 16 are respectively a plan view and a face view of the end leveling or trimming cutter of the cutter head.

Fig. 17 is a fragmentary section of an end of a barrel showing the various cuts performed by the machine.

The machine illustrated in the drawings as an embodiment of this invention, comprises, generally, a pair of barrel supports arranged on spaced, sliding guides, one of the barrel supports being fixed to the guides and movable therewith, while the other barrel support is slidable on said guides relatively to the first barrel support. The support which is fixed to the guides is further provided with a novel centering device, such that the barrel may be moved into operative relation thereto by the other barrel support, and said device is provided with means adapted to cooperate with the truss hoop on the adjacent end of the barrel, so that the truss hoop will constitute a gage for definitely positioning or centering the barrel in the centering device, and positively determining the length to which the end of the barrel is finished off. The sliding bar-

rel support is adapted to be moved on the guides to engage one end of a barrel and press it into engagement with the centering device on the first support, and the two barrel supports are adapted, after the barrel has been gaged and centered, to be moved together with the barrel to a position in which an end of the barrel is presented to a rotating cutter head on which are arranged the various cutting devices adapted to perform the chamfering, leveling off and crozing operations. The machine is further provided with adjustable stop and return means whereby the leveling operation may be stopped at any desired relative distance from the truss hoops, after which the parts may be returned to inoperative position so that the barrel may be easily accessible for removal from the machine.

In the particular embodiment of the invention shown in the drawings, there is provided a pair of barrel supports A A' which are respectively provided with spaced tubular bosses 10, 11 by which they are supported on a pair of parallel guide bars 12. The guide bars 12 are slidably arranged in bearing brackets 13, 13^a at opposite ends of a base frame B of any suitable construction. The barrel support A is adapted to slide or have free movements on and relatively to the bars 12, while the other support A' is adjustably secured to the bars 12 so as to move therewith, as by means of set screws or the like 14. The barrel supports A A' are normally spaced apart a distance somewhat greater than the length of the barrel to be operated on, and curved and sloping rests 15 and 16 respectively are provided, on which the barrels are placed. The centers of the arcs on which these rests are curved should be substantially coincident with the horizontal axis of the cutter head so that the axis of the barrel, when in position thereon, is substantially horizontal and substantially in alignment with said axis. To this end, the rest 15 is in the form of a separate member having opposite spaced lugs 17 provided with elongated slots 18 through which securing bolts 19 pass, whereby the rest may be adjusted relatively to the back stop portion 20 of the support A, see Fig. 3. The other rest 16 is similarly adjusted on the barrel support A' by means of bolts 17^a passing through slots 18^a in the rest to permit the rest to be moved vertically relatively to the support. This arrangement provides an initial adjustment whereby a barrel may be properly aligned with the centering device and the cutter head. After a barrel has been placed on the rests 15, 16, the barrel support A is moved to bring the back stop 20 into engagement with the adjacent rear end of the barrel X, the movement being continued to slide the barrel on the rest 16 into engagement with said centering means.

Any suitable means may be used for so moving the support A, that shown in the drawings comprising a transverse rock shaft 25 journaled in bearings 26 on the base B 5 and having crank arms 27 connected by links 28 to the back stop 20 of the barrel support A. A lever 30, fixed to one end of the rock shaft 25 enables the necessary movements of the shaft and described connections to be 10 made, so that the support A may be moved from its inoperative position, Fig. 1, to the positions shown in Figs. 5 and 6 by swinging the lever towards the right in Fig. 1.

As before stated, the temporary truss 15 hoops, designated X', are driven on the barrels so that they are a predetermined fixed distance apart on all barrels of the same size, regardless of slight variations in the lengths of the staves. When, therefore, a barrel has 20 been placed on the supports A A', the hoops X' resting on the supporting faces of the rests 15, 16, the support A is moved towards the support A' by the lever 30. This first causes the barrel support A to move relatively to the guide rods 12 until the left hand or rear end of the barrel is engaged by the back stop 20, the continued movement towards the right will shove the barrel on the rest 16 until the right hand truss hoop 25 engages with a centering and gage device C secured on the barrel support A. The continued right hand movement of the lever 30 will, by the pressure exerted by the support A through the barrel X against the centering device C, cause the two barrel supports A A' and the rods 12 to move together to a 30 position adjacent a rotatable cutter head D, where the barrel and its supporting devices will be arrested by suitable means, to permit the various cutting devices on the head D to act upon the right hand end of the barrel. After this end of the barrel has been operated upon, the parts of the machine are returned to inoperative position, in which the barrel is released from the centering and gage device. The operator then reverses the barrel end for end on the machine and the other end is operated on in a similar manner.

The centering and gage device C preferably comprises an annular flat plate or ring 32, extending transversely across the machine and adjustably supported in a vertical plane on the barrel support A' with its inner circular edge 33 substantially coincident with the curved rear edge of the rest 16, see Figs. 5 and 6. This inner edge 33 is preferably tapered or beveled and corresponds with the diameter and bevel of the truss hoops X' on the barrel X, so that the truss hoop adjacent thereto, when moved toward it will slide on the rest 16 into the aperture formed by the edge 33 where it will be frictionally held by the coaxing tapered faces, as long as pressure is maintained against the opposite end 60 of the barrel.

Means are provided whereby the centering and gage ring C may be adjusted relatively to, and held in adjusted position on the barrel support A', so that the barrel, when in operative position therein, will be properly centered relatively to the cutter head D. For this purpose the centering ring is formed with a true outer circular edge 34, concentric with the inner edge 33, and the barrel support A' is provided with spaced 70 lugs 35 having threaded apertures, in which turn radially arranged adjusting screws 36 are adapted to bear against the edge 34, see Fig. 4, preferably near the rods 12. The ring C is further provided with slots 37, and the adjusting bolts 17^a which extend through the slots 18^a of the rest 16 are adapted to pass through these slots 37, to adjustably secure the ring C on the support A', and to permit the ring, when the bolts 17^a are loosened, to be adjusted on the support. The slots 37 permit a limited movement of the ring vertically and laterally with reference to the axis of the cutter head, whereby the ring may be truly centered without the necessity of any accurate machine work or fitting on the barrel support A' other than to insure that the apertures for the rods 12 are formed the correct distance apart. Therefore, no great accuracy is required in 80 positioning the support itself, as all adjustments may be made by the use of the bolts 17^a, after the parts are assembled. After adjustment, the centering ring C is secured 85 in position by tightening the bolts 17^a. 90

A plurality of the centering and gage rings C are provided, having different inside diameters, adapted to cooperate with the truss hoops on barrels of different sizes, but all of these supplementary rings C are of 100 exactly the same outside diameter. In this way, it is only necessary to make one initial adjustment of the adjusting screws 36 to accurately center one of the rings C when the machine is first set up, after which any other ring of the same outside diameter will, when placed on the machine, be accurately centered, without further adjustment, by simply placing its peripheral edge in contact 105 with the ends of the two adjusting screws 36 and locking it in place by the bolts 17^a. 110

The cutter head D is mounted to revolve relatively to the adjacent end of a barrel. As shown in the drawings, the cutter head D is in the form of a wheel having a rim 40 with a beveled outer periphery and it is adapted to support a plurality of cutting devices, such as a chamfered device E, an end leveling or cutting off device F, and a crozing device G. The rim 40 has a reduced shoulder portion 41 on the side adjacent the barrel support A', whereby the end of the barrel X may surround, or extend inwardly beyond the face of the wheel D, so that the inner surface of the end of the barrel may 120 125 130

be moved into operative relation to the cutting devices without contacting with the cutter head D.

Any suitable means may be used for 5 mounting and rotating the cutter head D, that shown including a drive shaft 43 on which the hub of the head is keyed, as at 43^a. The shaft 43 is journaled in bearings 44, 45 and has tight and loose pulleys 46, 47 arranged thereon between the bearings 44, 45. A fly wheel 48 is also provided at the outer end of the shaft 43.

It should be understood that a plurality of the cutter heads D are provided having 15 rims of different diameters, so that when a centering device is changed for another one adapted to operate with a barrel of different size, a cutter head of suitable diameter is also substituted for the one that has been in 20 operation. The cutting devices are arranged on the cutter head D, so that as the barrel is advanced towards the cutter head, as explained, the chamfering or beveling device E first operates on the barrel, cutting 25 the material away gradually as the barrel advances, and after the chamfering operation has been partly completed, the leveling device F engages and cuts away and levels the ends of the staves, operating simultane- 30 ously with the chamfering device E, until the feeding advance of the barrel is arrested. After the advance movement of the barrel has been stopped and the chamfering and 35 leveling devices E and F have completed their work, the crozing device G is brought into action. This relative action of the cutters prevents the crozing device from operating during the longitudinal movement of the barrel, and cutting the croze in a spiral 40 path instead of in the intended true transverse path at right angles to the axis of the barrel.

As shown in the drawings, see Figs. 7, 13 45 and 14, the chamfering device E comprises a knife 55 adjustably secured on the rim 40 of the cutter head by means of a clamp 56 and screws 57 so as to project outwardly beyond the front edge of the head into the path of the barrel end to angularly engage 50 and cut away or bevel off the inner corners of the stave ends, as shown at 58, Fig. 17. This knife is shaped as shown so as to produce a drawing cut. The leveling device F, 55 see Figs. 7, 15 and 16, includes a cutting tool 59 disposed angularly across the face 40 of the cutter head in a clamp 60, in which it is adjustably held, as by a screw 61, so as to rotate with the cutter head D in the path of the advancing end of the barrel to engage 60 and trim off the ends of the staves, until the advance of the barrel is arrested.

The crozing device G is arranged on the cutter head D so as to be independently actuated; at the will of the operator, after the 65 chamfering and leveling operations have

been completed, to move radially relatively to the axis of the cutter head, so that the cutting element thereof will engage the inner faces of the barrel stave ends to form the usual croze for the reception of the barrel head. The crozing device is preferably pivoted eccentrically relatively to the axis of the cutter head D, and means are provided for swinging the crozing device on its pivot for limiting the depth of the croze, so 70 that the cutting tool is prevented from cutting clear through the staves and thereby spoiling the barrel. As shown in the drawings, Figs. 7-12, these parts are preferably constructed and arranged as follows: 75

A casting or block 65 is pivoted at 66 on a lug 67 extending inwardly from the rim 40 of the cutter head D, and is provided with a curved outer face arranged adjacent the plane of the inner face of the rim 40. The block 65 is disposed to swing transversely relatively to the cutter head D on its pivot 66 within a recess or cut-away portion 68 of the rim 40, and it is provided with the usual cutting tool 69 arranged transversely 80 and having an end 70 projecting laterally from the block adjacent the inner face of the barrel end. The tool 69 is adjustably secured in a groove or recess in the block 65, as by set screws 71. The normal inactive position of the crozing device shown in Fig. 7, is such that the cutter head may revolve freely within the end of the barrel without any part of the crozing device contacting therewith. The means for swinging the crozing device 85 G on its pivot 66 to move the tool 69 into engagement with the barrel as shown in Fig. 8, includes a collar 72, slidably arranged on the drive shaft 43, and provided with a longitudinally arranged rod 73 having a cam member 74 rigidly secured on its outer end. The block 65 is provided with a rearwardly projecting lug 75 having an inwardly projecting finger 76, which enters an inclined slot 77 in the cam member 74, see Figs. 10 90 and 11. If, therefore, the sliding collar 72 is moved from the position shown in Fig. 11 to that shown in Fig. 10, the finger 76 will slide in the cam slot 77, thereby moving the tool into engagement with the inner face of 95 the barrel end, as shown in Fig. 8. The outer face of the block 65 is provided with a cam or rib 80 so curved that, as the block 65 is swung on its pivot, a portion thereof at a distance from the cutting end 70 of the tool 100 will first engage the barrel, and continued movement of the block will permit a rocking action of the cam rib against the barrel so as to steady the block and permit the tool to cut gradually into the barrel to a depth 105 sufficient for a single cut around the inner face, after which the rib will enter the cut or groove so made and permit the tool to cut farther into the material. In other words, the cam rib 80 forms a gage to limit the 110

depth of the cut during each revolution of the cutting head so that the material of the barrel will not be splintered or deformed.

The crozing device G is further provided with an adjustable stop for limiting the final depth of the completed croze. The means shown comprises a stop screw or the like 81 in a threaded aperture in an arm 82 of the block 65, with its outer end arranged adjacent the inner face of the rim 40 of the cutter head. In the normal inactive position of the crozing device, the end of the stop screw 81 is positioned as shown in Fig. 7, the distance between it and the rim of the head D being first determined, after which it is locked in position by a locking nut or the like 83. Then, in operation of the crozing device, the tool can be swung on its pivot until the stop screw strikes the inner face of the rim 40 and prevents further cutting of the tool into the wood, regardless of the length of time the barrel is held by the lever 30 in operative relation to the cutter head.

Any suitable means may be used for sliding the collar 72 on the shaft 43, such as a hand lever 85, pivoted at 86 on the bearing 44, and having a fork provided with pins 87 which enter an annular groove 88 in the collar. By swinging the lever 85 in one direction on its pivot, the collar will be moved from the position shown in Figs. 2 and 11 to that shown in Fig. 10, with the cam 74 holding the tool 69 in cutting position. The collar is caused to turn with the cutter head by means of the cam rod 73 which passes through a hole in a flange 91 secured to the shaft 43 and rotatable with the cutter head D. A suitable spring 93 connected to the lever 85 and to a fixed part of the machine is adapted to return the lever and the collar 72 to the normal position.

The two operating levers 30 and 85 are so arranged that after a barrel has been placed on the barrel supports A A', the operator may grasp the lever 30 in the left hand the other lever 85 in the right hand, and after first swinging the lever 30 to center the barrel and present it to the cutter head, he may, after the chamfering and leveling operations have been completed, actuate the crozing device G by moving the other lever 85.

Means are provided for adjustably controlling the stop position of the barrel, which, as before explained, is moved as a unit with the barrel supports A A' and guide bars 12, so that the ends of the barrel may be trimmed or leveled off to any desired distance from the truss hoops X'. The preferred means for this purpose comprises a stop collar 100 adjustably secured, as by a set screw 101 on each of the guide rods 12, outwardly beyond the bearing brackets 13. To determine the stop position of the forward end of the barrel relatively to the cut-

ting devices, the various parts of the machine are brought to their inoperative position, with the lever 30 extending to the left, as in Fig. 1, and adjustable stop collars 102 on the rods 12 adjacent the bearing 44, are moved into engagement with this bracket. The stop collars 100 are now moved away from the brackets 13 a distance such that, when the barrel supports are moved to the right, and said stops engage the brackets 13, the forward ends of the staves will project beyond the centering ring C a distance that will ensure the staves being cut off the required distance from the truss hoops. The collars 100 are then secured on the guide rods 12 by their set screws. When the lever 30 is actuated and the barrel moved toward the right, the movement will continue until arrested by the engagement of the stops 100 with the brackets 13.

When the cutting operations have been completed, a movement of the lever 30 in the opposite direction will release the barrel by returning the barrel supports A A' to their normal positions, and the initial positions of all the parts will be assured by the engagement of the stop collars 102 with the bracket 44, preferably assisted by coil springs 103. When one end of the barrel has been so finished, the parts are returned to normal positions by reverse movements of the levers 30 and 85, thus permitting the barrel to be released from the centering and gage device C, so that it lies on the rests 15, 16 out of contact with the device C and back stop 20. The operator is, therefore, able to remove the barrel from the machine, turn it end for end and place it again on the barrel supports, after which the other end of the barrel may be chamfered, leveled and crozed in the same manner as the first end. Since the support A is independently movable relatively to the support A', the former support may be moved to properly engage the reversed barrel regardless of the fact that it is now shorter than before the first end had been trimmed.

We claim as our invention:

1. In a machine of the sort described, the combination of a rotatable cutter head, means for driving said head, a pair of supports having parts on which a barrel or the like may rest, operating means for simultaneously moving said supports with a barrel or the like thereon into operative relation to said cutter head, said cutter head including an annular rim supporting a plurality of cutting devices adapted to operate on the ends of said barrel, including a crozing device, said crozing device including a block adapted to swing in a plane at right angles to the axis of rotation of said head and being pivotally mounted eccentrically of said axis and normally at rest in a position out of contact with the inner wall of the barrel, a

crozing tool on said block, a sliding member movable longitudinally relatively to said head and having an inclined slot, a part on said block engaging in said slot, such that when said sliding member is moved in one direction said slot connection will cause said block to swing said tool into contact with the inner wall of said barrel, and when

moved in the opposite direction will cause said tool to be retracted from said barrel, and an adjustable stop member on said block adapted to engage a fixed part of said rim to limit the final depth of the croze formed by said tool. ¹⁰
